UNITED STATES PATENT OFFICE.

GEORGE C. THOMAS, OF NEW YORK, N. Y.

ART OF MAKING HINGES.

SPECIFICATION forming part of Letters Patent No. 267,809, dated November 21, 1882.

Application filed March 16, 1880. (No model.)

To all whom it may concern:

Be it known that I, GEORGE C. THOMAS, of the city of New York, in the county and State of New York, have invented certain new and 5 useful Improvements in the Art of Making Hinges of Sheet-Metal, of which the following is a specification.

My invention relates to hinges in which the two leaves or plates of the hinge are cut or 10 punched from sheet metal; and its object is to effect a saving of metal in the cutting of the blanks from which such leaves or plates are formed.

My improvements consist essentially in cutting or punching the blanks from sheet metal with the end portions diverging or extending 15 away from each other; in then bending said blanks to bring the end portions thereof into positions parallel with each other, and in finally 20 bending the extremities to form the ears or sockets and uniting the two parts by a pintle or pin.

In the accompanying drawings, Figure 1 represents a plan of the sheet-metal blank prior 25 to its being bent; Fig. 2 represents a similar view of the said blank after being bent transversely of its width, and Fig. 3 represents a plan view of the completed hinge.

Similar letters of reference designate corresponding parts in all the figures.

The blank for forming the leaf or plate of the hinge is first cut or punched from sheet-metal in the form shown in Fig. 1, in which the 30 end portions, A, are diverging or extend away from each other, preferably at an obtuse angle to the central portion, A', and when cut or punched in this form it is obvious that the blank can be cut from the metal side by side without waste, the two opposite sides of the 35 blank being of the same outline. The end portions, A, are joined to the central portion, A', by bends or curves a, so shaped that when pressure is properly applied to the blank it will yield at the said bends or curves and allow the 40 end portions, A, to bend into positions parallel with each other, as shown clearly in Fig. 2. In order to obviate the bending of the metal too much at the bends a, I preferably form a similar bend b at the middle of the central por-

tion, A', and when this is done the parts of the 50 central portion, A', which are upon each side of the bend b, are bent at an obtuse angle to each other, as shown in Fig. 3. This central bend, b, is, however, not absolutely necessary; but it has the additional advantage of imparting to the hinge an ornamental configuration.

The bending of the blanks transversely may be done by means of a die provided with cheeks or side pieces, inclined so as to bend the end portions inward toward each other, 60 and a pusher corresponding in shape with the outline of the inner edge of the finished blanks. The blanks are forced forward by the pusher, first bending them at the middle bend or curve, and afterward bending the end portions into 65 a position parallel with each other.

The blanks, bent into the form represented in Fig. 2, have the ends of the portions A shouldered at s, so as to engage properly to form a hinge, and bent over so as to form ears 70 or sockets c for the reception of the pintle or hinge-pin, d; and I may provide the hinge with the ordinary spiral spring, e, for automatically closing the door or other article to which the hinge is applied.

It is obvious that blanks of the form shown in Fig. 1 may be cut with much less waste of metal than if cut out in the form of the finished bent blank shown in Fig. 2, and as such hinges are usually made of sheet-brass, 80 this saving of material lessens the cost of manufacturing, and enables hinges to be produced at a cheaper rate, thereby proving a benefit to the manufacturer and the purchaser.

In lieu of the blank shown in Fig. 1, I may 85 employ blanks in which the end portions, A, extend parallel with the central portion, A', and are tangential to the bends or curves a.

What I claim as my invention, and desire to secure by Letters Patent, is—

1. The improvement in the art of making hinges of sheet metal—namely, cutting or punching the blanks from sheet metal with the end portions diverging or extending away from each other, bending said blanks to bring the end portions thereof into positions parallel with each other, and bending the extremities to form the ears or sockets and uniting the two

parts by a pintle or pin—substantially as set forth.

2. The improvement in the art of making hinges of sheet metal—namely, cutting the blank to the form substantially as shown in Fig. 1 of the drawings, bending said blank to the form substantially as shown in Fig. 2,

bending the extremities to form the sockets or ears, and uniting the two parts by a pintle or pin, substantially as set forth.

GEO. C. THOMAS.
